UNITED STATES PATENT OFFICE.

RICHARD HEATHFIELD, OF LONDON, ENGLAND.

GALVANIZING-MACHINE.

SPECIFICATION forming part of Letters Patent No. 707,322, dated August 19, 1902.

Application filed February 24, 1902. Serial No. 95,446. (No model.)

To all whom it may concern:

Be it known that I, RICHARD HEATHFIELD, a subject of the King of Great Britain, residing at 1 Leadenhall street, London, England, 5 have invented a new and useful Improvement in Galvanizing-Machines, of which the following is a specification.

This invention relates to machinery for coating metal sheets with metals, and especially to machines for galvanizing iron, and is directed toward improving present machines.

Hitherto a single pair of rolls has been arranged in the galvanizing-bath for clearing away superfluous metal from the sheet undergoing galvanization, said pair of rolls being arranged as a pair of partially-submerged exit-rolls by which the sheet is delivered from the bath of molten metal, said rolls being arranged close to the surface of the molten 20 metal in order that after the sheet has passed between them it shall be unable to become coated once more with superfluous metal.

My invention consists in providing an extra pair of rolls under and in close proximity to the exit-rolls, which I arrange submerged up to the nip in molten metal in order that superfluous metal may be more effectively removed from the sheet undergoing galvanization than has hitherto been the case, the 30 greater portion of said superfluous metal being removed by the additional pair of rolls which I provide and the remaining portion of the superfluous metal being removed by the pair of partially-submerged exit-rolls. In 35 order that the superfluous metal may be effectively removed, I arrange the extra pair of wholly-submerged clearing-rolls, which I provide as close to the exit-rolls as possible in order that after the sheet has passed through 40 the extra pair of rolls it may again take up as little superfluous metal as possible during its passage between the two pairs of rolls.

My invention also consists in providing specially-mounted guides between the pair of 45 clearing-rolls and exit-rolls and also between the edge of the bath at which the sheet enters and the clearing-rolls, said guides being hooked over tie-bars in order that if a sheet becomes stuck it can be readily released by 50 shaking the guides.

By the employment of a machine constructed according to my invention the amount of

coating metal which it is necessary to use in coating a sheet of given size is much reduced and, further, the general appearance of the 55 sheets is improved on account of the additional consolidating action provided by the extra pair of clearing-rolls.

The accompanying drawing illustrates in 60 sectional elevation a galvanizing-bath provided with the extra pair of clearing-rolls and the specially-mounted guides as arranged according to my invention.

In said drawing, 1 2 form the pair of partially-submerged exit-rolls, below and in close 65 proximity to which the rolls 3 4, forming the extra pair of clearing-rolls, are arranged, and between these two pairs of rolls the two guides 5 6 are situated, said guides being provided with hooks 7 8, which are hooked over tie-bars 70 8 8, passing between the frames 9, which support the rolls at their two ends, said frames being supported on the bath 10. The guide 11 is arranged to guide the sheet undergoing galvanization from the end 15 of the bath 10 at 75 which the sheet enters to the pair of clearing-rolls 3 4, said guide 11 being provided with hooks 12, which are hooked over a tie-bar 13. The upper guide 14 is fixed to the frames 9 in any suitable manner. The guides 5 6 insure 80 the sheet passing properly between the two pairs of clearing and exit rolls. If the sheet undergoing galvanization becomes stuck, it can readily be released by shaking the guides 5, 6, or 11. This can be effected by inserting a 85 bent rod between the rolls 1 and 3 and tapping the guides 5 and 6.

The pair of clearing-rolls 3 4 may suitably be driven by a spur-wheel 16, keyed on the axle of one of the rolls and engaging with a 90 spur-wheel 17, keyed on the axle of one of the exit-rolls 1 2, said spur-wheel 17 being driven in any convenient manner.

What I claim is—

1. In a galvanizing-machine, the combination of a bath containing molten metal, a pair of clearing-rolls wholly submerged in the molten metal, and a pair of exit-rolls partially submerged in the molten metal, the clearing-rolls being arranged below and in close proximity to the exit-rolls in order that after the submerged rolls have cleared away superfluous metal from the sheet undergoing galvanization, the sheet may pass through as

- little molten metal as possible, substantially as described.
2. In a galvanizing-machine, the combination of a bath containing molten metal, a pair of clearing-rolls wholly submerged in the molten metal, and a pair of exit-rolls submerged up to the nip in the molten metal, the clearing-rolls being arranged below and in close proximity to the exit-rolls in order that after the submerged rolls have cleared away superfluous metal from the sheet undergoing galvanization, the sheet may pass through as little molten metal as possible, substantially as described.
3. In a galvanizing-machine, the combination of a bath containing molten metal, a pair of clearing-rolls, wholly submerged in the molten metal, and a pair of exit-rolls partially submerged in the molten metal, the clearing-rolls being arranged below and in close proximity to the exit-rolls in order that after the submerged rolls have cleared away superfluous metal from the sheet undergoing galvanization, the sheet may pass through as little molten metal as possible, and guides arranged between the pair of clearing-rolls substantially as described.
4. In a galvanizing-machine, the combination of a bath containing molten metal, a pair of clearing-rolls wholly submerged in the molten metal, and a pair of exit-rolls partially submerged in the molten metal, and frames arranged on the bath and supporting said pairs of rolls, the said clearing-rolls being arranged below and in close proximity to the exit-rolls in order that after the clearing-rolls have cleared away superfluous metal from the sheet undergoing galvanization, the sheet may pass through as little molten metal as possible, and guides arranged between the pair of clearing-rolls and the pair of exit-rolls, and upper and lower sets of guides leading to the clearing-rolls, the upper set of which guides is fixed to the frames supporting the rolls and the lower set of which is at one end supported on the edge of the bath and at the other end is hooked over a tie-bar passing between the frames supporting the pairs of rolls, substantially as described.
5. In a galvanizing-machine, the combination of a bath containing molten metal, a pair of clearing-rolls wholly submerged in the molten metal, and a pair of exit-rolls partially submerged in the molten metal, and frames arranged on the bath and supporting said pairs of rolls, the said clearing-rolls being arranged below and in close proximity to the exit-rolls in order that after the clearing-rolls have cleared away superfluous metal from the sheet undergoing galvanization, the sheet may pass through as little molten metal as possible, and a set of guides arranged between the two pairs of rolls on each side of the path of the sheet undergoing galvanization, each set being provided with and supported by hooks hooked over tie-bars passing between the frames supporting the pairs of rolls, substantially as described.
6. In a galvanizing-machine, the combination of a bath containing molten metal, a pair of clearing-rolls wholly submerged in the molten metal, and a pair of exit-rolls partially submerged in the molten metal, and frames arranged on the bath and supporting said pairs of rolls, the said clearing-rolls being arranged below and in close proximity to the exit-rolls in order that after the clearing-rolls have cleared away superfluous metal from the sheet undergoing galvanization, the sheet may pass through as little molten metal as possible, and a set of guides arranged between the two pairs of rolls on each side of the path of the sheet undergoing galvanization, each set being provided with and supported by hooks hooked over tie-bars passing between the frames supporting the pairs of rolls, and upper and lower sets of guides leading to the clearing-rolls, the upper set of which guides is fixed to the frame supporting the rolls and the lower set of which is at one end supported on the edge of the bath and at the other end is hooked over a tie-bar passing between the frames supporting the pairs of rolls, substantially as described.

In testimony whereof I have signed my name to this specification in the presence of two subscribing witnesses.

RICHARD HEATHFIELD.
